UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 30, 1930. Serial No. 448,553.

This invention relates to refrigerating apparatus and more particularly to refrigerating apparatus of the absorption type.

For one of its objects, this invention contemplates employing, in absorption refrigerating apparatus, an improved method of removing or carrying away the exhaust fuel gases from the vicinity of the generator.

A further object of this invention is to provide a positive forcing or suction means for positively withdrawing or carrying away the exhaust fuel gases from the vicinity of the generator. More specifically, to provide such a positive forcing or suction means that will be operated by forces incident to the successful operation of the apparatus.

A still further object of this invention is to remove the exhaust fuel gases from the vicinity of the generator by means of instrumentalities operated by the flow of cooling water to or from the condenser.

Further objects and advantages of the present invention will be apparent from the following description, reference being had to the accompanying drawing, wherein a preferred form of embodiment of the invention is clearly shown.

In the drawing:

The figure is a view in vertical section through a refrigerator cabinet employing apparatus embodying features of my invention.

In the use of refrigerator cabinets mechanically cooled by means of absorption refrigerating apparatus in which the generator or the generator-absorber is heated by means of a combustible fuel, the cabinets must generally be placed, either in the household or in public stores or the like, where the exhaust gases are obnoxious. This invention has particular reference to a method of and apparatus for removing the noxious gases from the vicinity of the refrigerating apparatus.

To illustrate one use of my improved method and apparatus, I have disclosed a refrigerator cabinet in the form of an ice cream cabinet 10 having a refrigerated compartment 11 and a machine compartment 12. The refrigerated compartment includes a brine tank 13, surrounded by the insulating walls 14 and provided with one or more sleeves 15

for the reception of the commodities to be cooled, such as, for example, a can of ice cream. The refrigerated compartment 11 is cooled by an absorption refrigerating machine including the evaporator E located within the brine tank 13, and connected by means of a conduit 20 to the generator-absorber-condenser apparatus generally indicated by the reference character 21.

The generator-absorber-condenser unit 60 may be of any known construction. In this particular case, a unit similar to that disclosed in the application of Harry F. Smith, Serial No. 392,341, has been disclosed, merely for the purpose of illustrating the invention. It includes a cylindrical container 32, forming the generator-absorber proper and containing a quantity of solid material capable of absorbing and liberating large quantities of a refrigerant gas under varying degrees of temperature. A bleeder tube 33 passes down through the middle of the container 32 and is provided with a plurality of perforations throughout its length for the passage of refrigerant gas from the bleeder tube into the absorbent material, and from the absorbent material into the bleeder tube. One end of the bleeder tube 33 is connected by means of a conduit, not shown, to a condenser conduit located within the condenser C, the condenser conduit being in turn connected by means of a conduit 35 to the conduit 20, said connection being made through a controlling device K, which will be described hereinafter.

The generator 32, in this particular modification, is heated by means of the so-called vapor heating system. This vapor heating system includes a cylindrical container 36 surrounding and spaced from the generator container 32, forming a jacket 34, which jacket communicates at its upper end, through a conduit 37, controlling device K, and conduit 38 with a second condenser conduit also enclosed within the condenser C. A conduit 39, communicates with the other end of this second condenser conduit and with the lower end of the jacket 34 thereby forming a closed circuit for a volatile liquid contained within the container 36. Surrounding the container 36, and spaced therefrom, to form

- a jacket 39 is a third container 40 which forms the housing for the generator-absorber. This container 40 is surrounded and enclosed by the insulating material 41. At its upper end the jacket 39 between the containers 36 and 40, communicates with a flue 44 for conducting the exhaust fuel gases from the vicinity of the generator absorber. At its lower end the said space communicates with the container 45 secured to the outer container 40 by bolts 41 and in which is located a fuel supply burner 66, the supply of fuel thereto being controlled by means of the controlling device K, hereinafter described.
- 15 Cooling water for the condenser enters the system through the conduit 50 and, passing through condenser C, flows through the controlling device K and leaves the system through the conduit 46 which, as shown, discharges into the flue 44. The flue 44 at the point where the conduit 46 discharges thereinto is provided with a restriction forming in effect a Venturi or suction nozzle 76, operative to withdraw the exhaust gases from 20 the jacket 39 through the flue 44.

It should be noted that the apparatus is rendered entirely automatic and safe by means of the controller K. This controller has not been disclosed in detail. It may be 30 said however, that it may contain mechanism, as disclosed in the aforesaid application of Harry F. Smith, Serial No. 392,341, for controlling the supply of fuel to the burner in response to conditions within the vapor heating system and to this end, the vapor heating circuit has a portion passing through said controller, as for instance, the connection between the conduits 37 and 38. This control of the fuel supply may also depend upon the 35 flow of cooling water to the condenser which in this apparatus is designed to flow continuously during both absorbing and generating periods.

During the absorbing period, the vapor- 40 heating system becomes a cooling system, the heat of absorption being taken up by the volatile liquid in the jacket 34 and dissipated to the cooling water flowing through the condenser C, the rate of flow being governed by 45 the pressure within the conduits 20 and 35.

In operation, during the heating cycle, gaseous or other combustible fuel flows to the burner 66 under the control of the controlling device K. During this period, the 50 circulation of volatile liquid within the vapor-heating circuit is prevented. Heat being applied to the jacket 34 causes the volatile liquid in jacket 34 to vaporize, and condense on the sides of the generator 32, thus heating the said generator.

Water is flowing through the condenser, and emerging through the conduit 46 exhausts into the flue 44 at the Venturi nozzle 46, thereby lowering the pressure at the nozzle and causing the exhaust fuel gases to

be withdrawn through the flue 44 to be discharged to waste.

Thus the exhaust, obnoxious gases are removed from the vicinity of the generator.

While the form of embodiment of the invention as herein disclosed constitutes a preferred form, it is to be understood that other forms might be adopted, all coming within the scope of the claims which follow.

What is claimed is as follows:

1. In refrigerating apparatus including a condenser, a generator, and a fuel supply burner for heating said generator, the improved method which comprises, heating the generator by burning a combustible fuel, 80 cooling the condenser by circulating a cooling medium in heat exchange relation therewith, and withdrawing the exhaust gases from the vicinity of said generator by the suction action of the cooling liquid flowing 85 away from said condenser.

2. Refrigerating apparatus including a generator, a container surrounding and spaced from said generator to form a jacket, a fuel supply burner for heating said generator, said burner communicating with the lower end of said jacket, a condenser including a conduit for a cooling fluid in heat exchange relation with said condenser, said conduit being provided with a restricted 90 passage forming a Venturi nozzle, and a second conduit communicating with the upper end of said jacket and with said first named conduit adjacent the Venturi nozzle, whereby the exhaust fuel gases may be withdrawn from said jacket by the cooling fluid 95 passing through said first named conduit. 100

3. Refrigerating apparatus including a generator, a fuel supply burner for heating said generator, a condenser connected to said generator, means for cooling said condenser including a conduit in heat exchange relation with said condenser, said conduit being provided with a Venturi nozzle and means communicating with said Venturi nozzle for 110 removing the exhaust fuel gases from the generator.

4. Refrigerating apparatus including a generator, a container spaced from and surrounding said generator, and forming a 115 jacket, a fuel supply burner for heating said generator and communicating with the lower end of said jacket, a flue connected to the upper end of said jacket, a condenser connected to said generator, means for cooling 120 said condenser including a conduit in heat exchange relation with said condenser, said conduit discharging into said flue substantially as described.

In testimony whereof I hereto affix my signature.

HARRY B. HULL.
